UNITED STATES PATENT OFFICE.

FRANK E. SMITH, OF SCOTTDALE, PENNSYLVANIA.

LOADING MACHINE.

Application filed September 21, 1922. Serial No. 589,515.

To all whom it may concern:

Be it known that I, FRANK E. SMITH, a citizen of the United States, and resident of Scottdale, in the county of Westmoreland and State of Pennsylvania, have invented certain new and useful Improvements in Loading Machines, of which the following is a specification.

This invention relates to loading machines and while not limited thereto, relates particularly to loading machines adapted to load coal and other mined materials within a mine.

One object of this invention is to provide a machine loader that is capable of operation in the comparatively low mines, and one that may be adjusted as to height.

Another object is to provide a novel form of dipper or scoop for handling the material, and novel operating and control mechanism therefor.

Another object is to provide a machine of this class with a caterpillar traction base having a three-point suspension mounting which may be locked to form a four-point suspension when desired.

A further object is to provide a loading machine of this class with an endless conveyor for conveying the material rearwardly of the machine.

A still further object is to provide a loading machine of this class having the novel construction, design, and combination of parts hereinafter described, and illustrated in the accompanying drawings, in which—

Figure 1 is a side elevation of a mining machine constructed according to this invention, shown in position to begin a scooping operation.

Figure 2 is a similar view showing the scoop in a raised or dumping position.

Figure 3 is a sectional side elevation of the forward portion of the machine on a large scale.

Figure 3^a is a similar view of the rear portion of the machine continuing from the line X—X of Figure 3.

Figure 4 is a longitudinal sectional elevation of the forward portion of the machine, taken on the center line of the machine.

Figure 4^a is a similar view of the rear portion of the machine, continuing from the line Y—Y of Figure 4.

Figure 5 is a sectional plan of the forward portion of the machine. 55

Figure 5^a is a similar view of the rear portion of the machine continuing from the line W—W of Figure 5.

Figure 6 is a cross sectional elevation 60 taken on the line VI—VI of Figure 5.

Figure 7 is a similar view taken on the line VII—VII of Figure 5^a.

Referring particularly to the drawings, the numeral 2 designates the structural 65 base frame of the machine. A horizontal two track boom 3 extends parallel with and above the base, and is supported on inclined uprights 4 at each end. The uprights are pivotally secured to the base 2 70 and boom 3 so as to allow collapsing thereof.

The boom is held in its raised position by supports or standards 5 adjacent its rear end, which have their upper ends pivotally 75 secured to the boom and their lower ends secured in one of a series of adjustment holes 6 in brackets 7 on the base 2. The supports 5 are inclined in a direction opposite to the uprights 4 and have a break 80 joint 8 intermediate their ends adapted to be released to permit the quick lowering of the boom and adjustment of its height by securing the lower ends of the supports 5 in one of the other holes 6. 85

The base 2 of the machine is provided with caterpillar crawlers, comprising crawler chains 10 which are trained around drive sprockets 11 at one end and idler sprockets 12 at the other end. The 90 sprockets are mounted on stub shafts 14 journaled in the crawler frames. The base or main frame 2 consists of hollow side girders composed of side plates 15 and top channel 15^a which are tied together by a 95 transverse plate 15^b, cross girder 15^c, shaft 13 and other structural members as is common in the art. The crawler frames are also of hollow girder construction and each consists of two side plates 16 and a top 100 plate 16^a. The crawler frames are pivotally mounted at their rear ends on the shaft 13,

and have a plurality of traction wheels 17 journaled at spaced intervals along their length to provide a traction surface for the crawler chains 10. The load received by the main frame or base 2 is transmitted to the crawler frames, and thence through the traction wheels and sprockets to the crawler or caterpillar chains 10 and ground.

The crawler chains are propelled by means of power applied to drive sprockets 11. Power is transmitted to these sprockets through bevel gears 18-18^a and shafts 19. The shafts 19 are connected by gears 20 and 21 and clutches 22 to a shaft 23, and this shaft is in turn connected or geared to the main drive shaft 24 of the machine by gears 25 and 26, the gear 26 being connected to shaft 24 by clutch 27. The shaft 24 receives its power from a motor 28 which is connected to the shaft 24 by a sprocket and chain drive 29.

In operation, if both clutches 22 and clutch 27 are engaged, both crawler chains will move in unison. If one of the clutches 22 is disengaged, only one of the chains 10 will move and a turning action will take place. That is, the base will swing around on the stationary chain. The clutch 27 will be disengaged when the crawlers are desired to remain stationary while the motor 28 operates the other parts of the mechanism.

A dipper B having upwardly extending arms 31 on each side thereof is mounted to ride on the boom 3. An axle or cross shaft 32 is journaled in the upper ends of the arms 31 and has wheels 33 journaled on its outer ends which are mounted to ride between the flanges or tracks 34-35 of the boom. The dipper or scoop bucket comprises a body portion composed of bottom 36 having teeth 36^a on its front edge, sides 37, of which the arms 31 are an integral part, and a back composed of discharge doors 38 and 39. The sides 37 are tied together by a cross shaft 37^a which serves to stiffen the dipper.

The dipper or scoop bucket B is adapted to be reciprocated or moved into and out of the material to be loaded by rams 40-40 which are pivotally mounted on each side of the dipper and extend rearwardly therefrom. The rear ends of the rams are bent downwardly to provide engaging hook portions 41 which engage between the links of ram feed chains 42. The chains 42 are prevented from sagging by angles 42^a and are trained around drive sprockets 43 on ram drive shaft 44, journaled in bearings 45 on the base 2, and around idler sprockets 46 journaled in brackets 47 secured to the base 2. The shaft 44 receives its power from the shaft 24 through clutch 50 and chain 51, which is trained around sprockets 52 and 53, and the gears 48 and 49. The sprocket 53 is keyed on a hub extension of the gear

49 which in turn is loosely mounted on the shaft 13 so that the shaft 13 remains stationary. In operation the movement of the rams and dipper will be controlled by the operation of the clutch 50, or by starting, stopping, and reversing the motor 28.

Control cables 55 are secured to the upper ends of arms 31 of the dipper and trained rearwardly and wrapped around drums 56 secured on a shaft 57 journaled in the boom. The tension on the cables 55 imparts a torsion to the shaft 57 which tends to rotate this shaft. However, rotation of the shaft is normally prevented by a ratchet 58 and pawl 59. The ratchet 58 is rigidly connected to the right hand drum 56, and the pawl 59 is mounted on a sleeve 60 which is mounted to rotate freely on the shaft 57. The sleeve 60 has a friction clutch connection 61 with a sprocket 62 which is connected to the ram drive shaft by a timing chain 63.

The left hand drum 56 has a brake rim portion 64 and a brake band 65 is mounted thereon adapted to hold the shaft 57 stationary.

The above construction gives a positive connection between the ram driving shaft and the shaft 57. If the brake band 65 is tightened while the timing chain 63 is advancing, pawl 59 will snap over the ratchet 58 and allow the cables 55 to remain stationary and the rams 40-40 to advance. This operation will swing the dipper in an arc upward. If the brake is released while the rams 40-40 are still advancing, the raised position of the dipper will hold, due to the ratchet 58 and pawl 59. Considering the dipper in a raised position, if the clutch 61 is released, the cable will run freely ahead allowing the dipper to fall, and the falling movement may be controlled by the degree of the release of the clutch. If the motor is reversed, the direction of travel of the ram chain will be reversed and the timing chain will also be reversed. Consequently the drums 56 will be reversed so as to take in the cable 55. It will thus be understood that the above arrangement permits, at the control of the operator, a raising or lowering of the dipper, and automatically holds the relative position when once set. By this control the operator may move the dipper to any point within its reach. That is, he can advance straight, lower or raise, and advance on an angle. This absolute control of the dipper is very essential and greatly facilitates the loading of coal.

A belt conveyor 67 for receiving the material to be loaded from the dipper and conveying to the rear of the machine is trained over head and tail pulleys 68 and 69, respectively, mounted on shafts 70 and 71, and supported intermediate its ends by rollers 72. The shaft 70, carrying the head pulley, is driven by a motor 73 connected to a

countershaft 74 by drive chain 75. The countershaft 74 is provided with a pinion gear 76 in mesh with a gear 77 on the shaft 70.

5 The conveyer is provided with suitable flights 78 to prevent slipping of the material being conveyed, and suitable shirt boards 79 are arranged along each side of the conveyer to prevent spillage.

10 As said before, the dipper B is provided with back discharge doors 38 and 39, which doors are adapted to be opened when the dipper is in a raised position over the conveyer 67. The lower door 38 is hinged to the bottom of the dipper by a hinge 80 and is so constructed that when it is released it can swing around the hinge 80 until it is in a plane with the bottom 36. The upper door 39 is keyed to a shaft 81 journaled in the sides 37 of the dipper. The doors 38 and 39 are connected together by levers 82 keyed to shaft 81 and connected to the door 38 by links 83. A locking arm 84 is keyed to the shaft 81 and is adapted to engage a spring pressed latch 85 on one of the arms 31 of the dipper. It will thus be seen that the doors are normally locked in closed position. However, when the dipper B is in raised position the load on the doors and the weight of the doors has a tendency to force the doors open, so that when the latch 85 is released the doors will automatically open and discharge the material onto the conveyer 67. The latch 85 is adapted to be operated by a latch rope 86, which has one end fixed to the forward end of the boom, and is trained over a sheave 87, down and under sheave 88 on the latch, up and around sheave 89, and thence to the rear end of the boom where it is led to a suitable place convenient for the operator.

15 A three-point equalizing suspension for the crawler frames is formed due to the mounting of the crawler framed at their rear ends on the fixed shaft 13 and leaving them free at their forward ends. An equalizing shaft 90 is journaled in suitable bearings in the main frame or base 2 and is connected to the crawler frames through pinions 91-91^a keyed to the shaft, and meshing with racks or gear segments 92-93, respectively, secured to the crawler frames. The gear segments 92 and 93 are on the opposite side 20 of their respective pinions 90-91. The load is equally distributed on each crawler. Therefore, if one crawler is raised higher than the other, the shaft 90 will be rotated due to the gear and rack connection with the crawler frame, and thus the other crawler will be forced down a distance equal to the amount the other crawler was raised.

25 The shaft 90 is provided with brake drums 95 having brake bands 96 thereon, which bands are adapted to be tightened or ap-

plied to lock the shaft 90 against rotation 65 when it is desired to form a four-point suspension for the crawler frames.

30 Suitable operating levers are indicated for the various clutch brakes and other operating parts. However, these levers are shown broken away in most views for the sake of clearness. It will be understood, however, that these levers may be in the form of any well known design commonly used for such purposes.

35 It will be understood that various modifications will readily suggest themselves to those skilled in the art, and while I have only shown one preferred form of my invention, I do not wish to be limited thereto, since many modifications may be made within the scope of the appended claims.

I claim:

1. A loading machine comprising a movable base, a horizontally disposed vertically adjustable and collapsible boom above said base, a dipper supported from said boom and means for actuating said dipper.

40 2. A loading machine comprising a movable base, a horizontally disposed vertically adjustable and collapsible boom above said base, a dipper movably supported on said boom, and a pair of rigid rams for moving said dipper into the material to be loaded.

45 3. A loading machine comprising a movable base, a horizontal boom supported above and adjustable vertically relative to said base, a dipper, arms extending upwardly from each side of said dipper and movably mounted on said boom, means for moving said arms in one direction and limiting their movement in the other direction to raise, lower and tilt said dipper, rigid rams pivotally secured to each side of said dipper and extending rearwardly therefrom and means for reciprocating said rams to move said dipper into and out of the material to be loaded.

50 4. A loading machine comprising a movable base, a horizontal boom above said base, a dipper, rigid arms formed integral with said dipper extending upwardly from each side thereof and movably mounted on said boom, means for moving said arms in one direction and limiting their movement in the other direction to raise, lower and tilt said dipper, rams pivotally secured to each side of said dipper and extending rearwardly therefrom and means for reciprocating said rams to move said dipper into and out of the material to be loaded.

55 5. A loading machine comprising a movable base, a horizontal boom above said base, a dipper, rigid arms formed integral with said dipper extending upwardly from each side thereof and movably mounted on said boom, means for moving said arms in one direction and limiting their movement in

the other direction to raise, lower and tilt said dipper, rams pivotally secured to each side of said dipper and extending rearwardly therefrom, and endless drive chains for reciprocating said rams to move said dipper into and out of the material to be loaded and means for operating the means for moving said arms and said drive chains.

6. A coal loading machine for mines, comprising a movable base, a horizontal boom above said base, a dipper, arms extending upwardly from each side of said dipper and movably mounted on said boom, rams pivotally secured to each side of said dipper and extending rearwardly therefrom, a drive shaft adjacent the rear of said machine, chains trained over sprockets on said shaft and over idler sprockets on a second shaft forward from said first shaft, said rams being engaged between the links of said chains and reciprocated thereby, a cable shaft, drums on said shaft, cables wrapped on said drums and secured to said arms to provide means for moving said arms in one direction and limiting their movement in the other direction, and driving means connecting said drive shaft and said cable shaft.

7. A coal loading machine for mines, comprising a movable base, a horizontal boom above said base, a dipper, arms extending upwardly from each side of said dipper and movably mounted on said boom, rams pivotally secured to each side of said dipper and extending rearwardly therefrom, a drive shaft adjacent the rear of said machine, chains trained over sprockets on said shaft and over idler sprockets on a second shaft forward from said first shaft, said rams being engaged between the links of said chains and reciprocated thereby, a cable shaft, drums on said shaft, cables wrapped on said drums and secured to said arms to provide means for moving said arms in one direction and limiting their movement in the other direction, driving means connecting said drive shaft and said cable shaft, and means for controlling the operation of said cable shaft.

8. A loading machine comprising a movable base, a horizontal boom above said base, a dipper, rigid arms formed integral with said dipper extending upwardly from each side thereof and movably mounted on said boom, means for moving said arms in one direction and limiting their movement in the

other direction to raise, lower and tilt said dipper, rams pivotally secured to each side of said dipper and extending rearwardly therefrom, and endless drive chains for reciprocating said rams to move said dipper into and out of the material to be loaded, power means for operating the means for moving said arms and said drive chains and controllable by the operator for rendering said power means inoperative as to the means for moving said arms.

9. A loading machine comprising a movable base, a horizontal boom above said base, a dipper, rigid arms formed integral with said dipper extending upwardly from each side thereof and movably extending upwardly from each side thereof and movably mounted on said boom, control cables for moving said arms in one direction and limiting their movement in the other direction to raise, lower and tilt said dipper, rams pivotally secured to each side of said dipper and extending rearwardly therefrom, endless drive chains for reciprocating said rams to move said dipper into and out of the material to be loaded, power means for operating said control cables and said endless drive chains and independent manually operated means for rendering said power means inoperative relative to either said control cables or said endless drive chains.

10. In a loading machine having a movable base, an endless conveyer mounted on said base, a horizontal boom, a dipper member having integral upwardly extending arms movably supported on said boom, a pair of discharge doors secured across the rear end of said dipper, means for interlinking said doors together to cause unison of movement, means for normally locking said doors in closed position, means controlled by the operator for releasing said doors and means for tilting said dipper to cause the material in the dipper to discharge through said doors and onto said endless conveyer.

11. A loading machine comprising a base of the self propelling crawler type, a horizontally disposed vertically adjustable and collapsible boom above said base, a dipper supported from said boom and means for operating said dipper.

In testimony whereof, I have hereunto set my hand.

FRANK E. SMITH.
